UNITED STATES PATENT OFFICE.

EDDIE M. OVERBEY, OF CREIGHTON, MISSOURI.

DUST-CAP FOR INFLATING VALVE-STEMS.

1,367,084.

Specification of Letters Patent.

Patented Feb. 1, 1921.

Application filed February 16, 1920. Serial No. 358,993.

To all whom it may concern:

Be it known that I, EDDIE M. OVERBEY, a citizen of the United States, residing at Creighton, in the county of Cass and State of Missouri, have invented certain new and useful Improvements in Dust-Caps for Inflating Valve-Stems, of which the following is a specification, reference being had to the accompanying drawings.

10 This invention relates to wheels with pneumatic tires, and particularly to a combined valve and dust cap to be normally disposed over the inflating valve stem.

15 The general object of my invention is to provide a valve cap of this character which may be easily applied to the valve stem or readily removed therefrom, and which, when in place, will absolutely prevent the access of dust to the valve stem, and in this 20 position will also prevent any possible leakage of air from the valve stem due to a leaky or worn valve within the valve stem or the presence of dust or other foreign matter in the valve which will prevent the 25 full closing of the stem.

A further object is to provide a valve cap of this character having within it a cover or stop adapted to close against the upper end of the valve stem, the cap being so 30 formed that when in locked position the cover will be clamped resiliently against the end of the valve stem, while the base of the cap will be urged resiliently and tightly against the felly of a wheel.

35 A further object is to provide a cap of this character which is adapted to be quickly engaged with the ordinary screw-threads found on the ordinary inflating valve or disengaged therefrom without the necessity 40 of screwing a dust cap onto the valve stem or unscrewing it therefrom, or tightening or releasing any nuts or other like parts.

45 A further object is to provide a valve cap of this character which may be easily applied, readily removed, and which is thoroughly effective in practice, and which eliminates the necessity of screwing on or unscrewing the valve cap, which is a more or less tedious operation, and which further 50 eliminates any chance of the valve cap being accidentally unscrewed and lost.

Other objects will appear in the course of the following description.

55 My invention is illustrated in the accompanying drawings, wherein:—

Figure 1 is a vertical longitudinal sec-

tional view of a tire inflating valve stem and cap constructed in accordance with my invention;

Fig. 2 is a section on the line 2—2 of 60 Fig. 1;

Fig. 3 is a side elevation of the base section of the cap;

Fig. 4 is a top plan view of the member 65 24;

Fig. 5 is a fragmentary sectional view diametrically through the valve stem and the inner sleeve;

Fig. 6 is a fragmentary elevation of the means for releasing the clamping member 70 75 35 from its engagement with the stem;

Fig. 7 is a cross section through one of the handles showing the latches therein, this view also showing the adjacent portion of the outer casing.

75 Referring to the drawings, A designates the stem of the ordinary inflating valve commonly used on bicycles, automobiles, etc., for the purpose of inflating the pneumatic tire, B designating the felly of the 80 wheel through which this inflating stem normally projects. The interior of the stem is provided with the usual valve for preventing the outward passage of air from the tire, this valve being adapted to be 85 forced inward and opened by the application of an inflating pump thereto in the usual manner. The interior construction of this valve stem and the valves therein form no part of my present invention, my present 90 invention relating entirely to the cap for inclosing the upper portion of the inflating stem and preventing the access of dust thereto or the exit of air therefrom.

95 The valve cap comprises essentially three main sections 10, 11 and 12. The section 10, as illustrated in Fig. 1, is annular in form and provided with an upwardly extending wall and a downwardly and outwardly flaring base 13. The upwardly extending wall 100 at opposite points in its circumference is provided with the slots 14, while the upper edge of this wall is channeled for a portion of its circumference, as at 15, and this channel terminates in a bore 16 in which a coil 105 spring, hereinafter referred to, is engaged. The end of this spring is disposed within this bore 16 and then extends outward and around the shaft in the base, and then extends upward, as will be later described. 110 The section 11 is larger than the upwardly extending wall of the section 10 and fits

thereover and is provided with inwardly extending pins 17 extending through the slots 14 and engaging an inner sleeve, as will be later stated. This section 11 is vertically slotted downwardly from its upper edge for a portion of its length, as at 18 and the outer face of the section on each side of this slot 18 being reduced in thickness, as at 19, and the opposite walls of the slot being 10 channeled, as at 20. The upper end of the portion 11^a of section 11 is exteriorly screw-threaded and the section 12, which is annular in cross section at its lower end, is interiorly screw-threaded to engage and 15 move with the section 11. The section 11 is made in two parts.

Sliding in the guides formed by the channels 20 are slides 21 which are longer than the slots 18, and which at their upper ends 20 are deflected inward, as at 22, and then extend upward in the form of rods 23, each rod having a nut at its upper end. Disposed within the upper section 12 is a closure or interior cap 24 having a circular body, somewhat concavo-convex, and provided with a rubber or like yielding gasket 25 on its inside face which is adapted to fit against and close the upper end of the inflating valve stem. The interior cap 24 is radially extended at opposite points, as at 26, to form arms, these arms being pierced for the passage of the rods 23. Disposed between the nuts or heads on the upper ends of these rods and the arms 26 35 are the compression springs 27. Thus, when there is a downward pull on the rods 23, it is obvious that the cap 24 will be forced with its gasket firmly against the upper end of the inflating valve stem.

40 Disposed within the sections 10, 11 and 12 and having a diameter slightly larger than the stem A, is an inner sleeve 28, this inner sleeve being slotted, as at 29, at one point in its diameter, the slot extending vertically 45 and being in alignment with one of the slots 18 in the section 11. This inner sleeve 28 at its lower end is engaged by the screw-threaded inner ends of the pins 17 which pass through the upper end of the section 10 and through the lower end of the section 11. At its upper end this inner sleeve is provided with sockets 30, these sockets 30 having screw-threaded engagement with the lower ends of bolts 31 which extend up 55 through the upper section 12 and have heads bearing against the top of this upper section. It will thus be seen that the inner sleeve 28 and the sections 11 and 12 move together and relatively to the base section 60 10 by reason of the pins 17 extending through the vertical slots in said base section. Disposed in the bore 16 of the base section and in the groove at the upper edge of this base section and then extending upward around the inner sleeve 28 is a spiral 65

compression spring 32 which, at its upper end, extends upward and around and bears upon the cap or closure 24 so that when the upper portion of this spring is under tension, it assists the spring 27 in urging 70 the cap 24 to its closed position against the upper end of the valve stem A.

For the purpose of engaging the dust cap with the screw-threads *a* of the valve stem A, I form the inner sleeve for a portion of 75 its diameter with six or more interrupted screw-threads 33, as shown in Fig. 5, these screw-threads having a pitch the same as the pitch of the screw-threads *a*. The diametrically opposite portion of the inner 80 sleeve is formed with a relatively large slot or opening 34 which has practically the same area as the area of the screw-threads 33, and in this opening is mounted a curved plate 35, the interior face of which is 85 formed with interrupted screw-threads corresponding to the screw-threads 33. This plate at one end is mounted upon a spring 36 which acts to urge the plate inward and thus carry the screw-threads into engagement with the screw-threads on the valve stem. This spring 36, as illustrated in Fig. 2, is attached at one end to the circular or arcuate, screw-threaded plate 35, and then extends through an opening in the exterior 95 of the sleeve 28 and is attached thereto by a pin 37. The opposite end of the section 35 is reduced in thickness, as at 38, so as to extend on the inner face of the inner sleeve beyond the slot 34 but in spaced relation to 100 the inner sleeve so that the screw-threaded clamp formed by plate 35 may be shifted outward by means which will be now described, the spring 36 acting to shift it inward. It will be obvious that when this 105 clamp section 35 is shifted out relative to the screw-threaded portion 33, that the inner sleeve will be free from engagement with the inflating valve stem A, and that when the spring urges this clamp 35 inward, it will 110 be in engagement with the screw-threads of the stem A and, therefore, the cap as a whole will be held firmly in place upon the inflating valve stem.

For the purpose of increasing or decreasing 115 the tension on spring 32 and shifting the clamp member 35 or locking member out of its engagement with the screw-threads *a*, I provide between the inner sleeve and the section 11 a ring, designated generally 39. 120 This ring at opposite points in its diameter is provided with screw-threads apertures 40, and passing through the slots 18 of the shell or section 11 are handles, designated generally 41. There are two of these handles, 125 each provided with a handle portion proper and squared portion 42 adapted to move up and down in the slot 18, and a shank 43, each shank intermediate of its length being screw-threaded, as at 44, and one of 130

these shanks at its extremity being screw-threaded, as at 45. An approximately triangular, wedge-shaped head 46 is engaged with this screw-threaded portion 45, and 5 this wedge is disposed normally just below the extremity 38^a of the portion 38 of the locking member 35 so that when the handles are moved up, this wedge will be forced against the free end of the member 35 and 10 will force this member 35 outward, thus releasing it when the wedge is forced downward. The spring 36 acts to force the member 35 inward and into screw-threaded engagement with the screw-threads of the 15 stem.

In order to hold the handles and the ring 39 in any desired adjusted position, both of the handles are formed outward of the squared portion 42, as illustrated in section 20 in Fig. 7, that is with the upper and lower triangular recesses 47 and 48. In the upper recess there is pivoted a catch 49 which, when it is turned into a horizontal position, bears against the bottom of the recess 47 and 25 projects laterally outward beyond the handle and is adapted to engage any one of a series of notches 50 formed in the lower end of the countersunk margin 19 of the slot 18. When the catch 49 is in its horizontal position and bearing against the bottom of the recess 47, it is obvious that the ring 39 and the handles attached thereto cannot move upward, but that the handles and ring can move downward. When, however, the 30 handles are moved upward and it is desired to hold these handles in their upwardly moved position, then the catch 49 is allowed to turn to a vertical position so as not to engage a series of notches 50 formed in the 35 upper end of the countersink 19, and the catch 51 which is pivotally mounted within the recess 48 is shifted outward to a horizontal position and bearing against the top of the recess 48 and any one of the notches 45 50 will prevent any downward movement of the handles and of the ring 39. It is to be understood that there are two series of these notches, one series 50 being adjacent the upper end of the countersink 19, while 50 the other series 50^a is adjacent the lower end of the countersink. This ring 39 is engaged with the spring 32 so that a downward movement of the ring 39 will compress the lower portion of the spring below the ring 55 39 and increase the pull and, therefore, increase the tension on the upper portion of the spring, and when this ring 39 is moved upward by the handles 41, the tension on the upper portion of the spring and the lower portion of the spring as well will be reduced. Therefore, it will be seen that when the ring 60 39 is forced downward, the lower portion of the spring 32 will exert a relatively strong pressure upon the upper end of the 65 base section 10, forcing this base section

against the felly of the wheel, while the upper portion of the spring 32 will be placed under tension so that it acts as a retractile spring to urge downward upon the cap 24. At the same time, the upward 70 movement of these handles will cause the wedge to release the engagement of the locking clamp 35 with the screw-threads *a* of the valve stem, while a downward movement of the handles will cause the wedge to 75 release its engagement with the member 35 and permit the spring 36 to force this member 35 into engagement with the screw-threads *a*. Preferably one of the handles is formed at its extremity, as at 52, to engage 80 the valve within the stem A so as to unscrew this valve and permit its removal or screw it up. In other words, the part 52 is a small, two-pronged wrench for this purpose.

The operation of this device is as follows: 85 When it is desired to apply the cap to the valve stem, the cap is disposed over the valve stem with its base 10 engaging against the inner face of the felly. Then the handles 41 are depressed, thus carrying the slides 21 90 downward, pulling downward on the rods 23 and causing the spring 27 to be compressed to thereby force the cap 24 against the top of the valve stem. The downward movement of the ring 39 relative to the 95 outer casing releases the locking member 35, which, by means of the spring, is urged inward into engagement with the screw-threads *a*, while the further downward movement of the ring 39 and of the handles 100 causing the compression of the lower portion of the spring 32, thus urging the base 10 firmly against the felly wheel. The upper portion of the spring is drawn downward, thus increasing the tension upon the 105 cap 24 and urging the cap into dust-tight engagement with the upper end of the nipple or valve stem A. In this position, the upper catches or catch 49 is shifted laterally and into engagement with the notches 50 110 and this locks the parts into closed position, and the cap is locked upon the nipple or valve stem.

Now if it be desired to remove the cap, each handle is depressed a trifle. This 115 causes the upper catches 49 to move upward to a vertical position, or these catches may be shifted by the fingers to a vertical position, and then the handles are released and permitted to move upward to a position 120 a trifle above the uppermost notches 50. The bottom handle catches 50^a are then pushed outward and upward so that they enter the notches 51 and the handle let down a trifle and the handles and the ring are 125 secured against further movement. The clamp release wedge 46 has moved into position against the free end of the locking member 35 and pushed it outward, thus releasing the cover or cap from the valve stem. 130

The cap can now be lifted off of the valve stem and the valve removed or air pumped into the tire as desired. It will be thus seen that the removal of the dust cap is very quickly secured, whereas to take off or put on the common dust cap, valve end cap and base nut requires several minutes.

The cap may be applied as quickly as it is removed. The cover is slipped over the 10 valve stem, the tire being inflated so that the valve stem is pushed firmly against the wheel felly. The handles are raised a trifle and the lower catches will drop by their own weight, which releases the handles and 15 the handles are forced downward. This lets the clamp member 35 engage the threads on the valve stem, fastening the cover firmly to the valve stem. The lowering of the catches also lowers the tension ring 39, and as the 20 handles are lowered, the part of the spring 32 below the tension ring 39 is compressed, as before stated, giving a strong downward pressure on the base member 10 which takes up any looseness between the cover and the 25 felly. Above the tension ring 39 the spring 32 is drawn downward, and as the top of the spring is fast to the valve sealing cap 24, it follows that the cap will be forced firmly against the upper end of the valve 30 stem. If the end of the valve stem is somewhat above the top of the inner sleeve 28, there will be sufficient downward pull on the cap 24 if the handles are left at the top 35 notch of the lower set of notches 50^a. If the valve stem is shorter, the handle should be set with the upper catches in the second of this set of notches 50^a. This will, of course, 40 urge the cap 24 more strongly to its seat as well as forcing the base 10 more firmly against the wheel felly. To set the upper catches, the handles are rotated slightly below the notches in which the catches are 45 supposed to engage and the top catches will drop into the notches. Then upon a release of the handle, the handle and ring will tend to move upward, thus locking the catches in the notches.

It will be seen that, as before explained, this dust cap may be very quickly applied 50 and as quickly removed, and that when it is in position on the valve stem, it is firmly locked thereto against any accidental displacement, and that it cannot come unthreaded from the valve stem because of the 55 frictional engagement between the base member 10 and the felly of the wheel. Further it will be seen that the device compensates for different lengths of valve stem and that if there is any leakage of air at the upper end of the valve stem it is an easy matter to increase the pressures of the springs 60 which force the closure 24 down upon the upper end of the valve stem. Again it will be noticed that the slots 18 are at all times 65 closed by the slides 21 so that no dust can

get in through these slots into the interior of the dust cap and so into the valve stem while the dust cap is in place.

While I have illustrated a particular form of my invention which I believe to be thoroughly effective in practice, yet I do not wish to be limited thereto, as it is obvious that many changes might be made therein without departing from the spirit of the invention.

I claim:—

1. A dust cap for inflating valve stems formed to inclose the stem, a valve stem closure disposed within the cap and adapted to bear against the upper end of the valve stem when the cap is in place, resilient means urging the said closure to its seat on the valve stem, and longitudinally adjustable means carried by the cap operatively connected to said resilient means to increase or decrease the tension on said resilient means to thereby force the closure into tight engagement with the valve stem or reduce pressure on the closure against the valve stem.

2. A dust cap for inflating valve stems formed to inclose the stem, means on the cap for engaging the stem, a valve stem closure disposed within the cap and adapted to bear against the upper end of the valve stem, a coiled spring engaging said closure and extending downward therefrom and within the cap, and means connected to the lower portion of said spring whereby the lower portion of the spring may be pulled 100 downward to thereby increase the resiliency of the spring, said means being vertically adjustable in a plurality of positions.

3. A dust cap for inflating valve stems comprising a body formed to inclose the stem, a base section longitudinally slidable on the lower end of the body, means carried by the body for detachably engaging the body with the valve stem, a spring yieldingly urging the base section away from the body to thereby yieldingly urge it against a felly, and means for increasing or decreasing the tension of said spring.

4. A dust cap for inflating valve stems comprising a body formed to inclose the stem, a base section slidably mounted on the body for longitudinal movement and adapted to engage with the felly of a wheel, means on the body for detachably engaging it with the valve stem and preventing longitudinal movement of the body with relation to the valve stem when so engaged, a closure for the valve stem mounted within the body, resilient means urging the closure toward the base section and the base section away from the body, and means for increasing or decreasing the tension of said resilient means to thereby increase or decrease the pressure on the closure and on the base section.

5. A dust cap for inflating valve stems having a body formed to inclose the stem, a base section slidably mounted on one end of the body and adapted to bear against the felly of a wheel, a cap disposed within the body and adapted to bear against the outer end of the valve stem, a coil spring connected at one end to said cap and at its other end bearing against the base section, and 10 manually adjustable means on the body and engaging said spring intermediate its ends for increasing or decreasing the pressure exerted by the spring upon the base section and increasing or decreasing the pressure 15 exerted by the spring upon the cap.
6. A dust cap for inflating valve stems comprising a body formed to inclose the stem, a base section longitudinally slidable upon the body and having telescopic engagement therewith and adapted to bear against a felly, a closure disposed within the body and adapted to close against the outer end of the valve stem, means on the body for engaging the valve stem to prevent longitudinal movement of the cap with relation thereto, a coil spring disposed within the body and connected at one end with the closure and at its opposite end bearing against said base section, and manually operable 25 means for decreasing or increasing the pressure of said spring on the base portion and the tension of the spring on the cap, said manually operable means being shiftable to disengage the locking means from the valve 30 stem or engage it therewith.
7. A dust cap for inflating valve stems comprising a body adapted to inclose the stem, means for locking the cap to the valve stem or releasing it therefrom comprising a 35 locking member having screw-threads disposed within the cap, a spring urging said locking member inward to engage the screw-threads on the valve stem, and a longitudinally movable manually operable member 40 which, when shifted longitudinally in one direction, forces said locking member out of engagement with said screw-threads, and when shifted in the other direction permits the locking member to engage the screw-45 threads.
8. A dust cap for inflating valve stems comprising a body formed to inclose the stem, and means for locking said body to the stem comprising an interiorly screw-threaded member, a spring supporting one end of the member and urging it inward toward the axis of the cap and thereby into engagement with the screw-threads of the stem, and a vertically movable manually operable 55 member mounted in the body and having a wedge at one end adapted, when the manually operable member is shifted, to engage said locking member and shift it outward against the force of the spring to thereby release the cap.
9. A dust cap for inflating valve stems comprising a body formed to inclose the stem and means for locking the body to the stem comprising an interior sleeve mounted within the body and adapted to closely surround the inflating valve stem, said sleeve being formed with a series of interrupted screw-threads engageable with the screw-threads of the valve stem and with a slot 60 opposite said screw-threads, a locking member normally disposed in said slot and having interrupted screw-threads, a spring supporting said locking member on said sleeve and urging the locking member inward toward the axis of the stem, and a manually 65 shiftable wedge mounted in the body and adapted to be shifted to a position to force the locking member outward or shifted to a position to release the locking member and permit the spring to urge it inward.
10. A dust cap for inflating valve stems comprising a body formed to inclose the stem and having a longitudinally extending slot, an interior sleeve supported within the body and adapted to closely fit the valve stem, one portion of the sleeve being provided with interrupted screw-threads and the opposite portion of the sleeve having a slot, a locking segment disposed in said slot and having interior screw-threads and resiliently supported at one end and being urged 70 inward toward the axis of the sleeve, and means for forcing said member outward comprising a handle extending through said slot and having a wedge at its inner end 75 adapted to engage the free extremity of the locking segment and force it outward when the wedge is shifted in one position.
11. A dust cap for inflating valve stems comprising a body formed to inclose the stem, the body being provided with oppositely disposed slots, a base section telescopically engaging the body for longitudinal movement, a closure disposed within the body and adapted to bear against the upper end of the valve stem, a coil spring bearing at one end against the base section and at its opposite end operatively connected to the closure, an inner sleeve adapted to closely surround the valve stem and formed with 80 longitudinally extending slots, one portion of the sleeve having interior screw-threads adapted to engage the screw-threads of the valve stem and the opposite portion of the sleeve being slotted, a locking segment disposed in said slot and having interior screw-threads, a spring supporting one end of the locking segment and urging the locking segment inward toward the axis of the sleeve, and means for increasing or decreasing the tension on the first named spring and engaging or releasing said locking segment comprising handles having shanks extending through said slots in the body and into the slots in the sleeve, one of said handles 85

- 130

carrying a wedge adapted, when the handle is shifted, to engage the locking segment and shift it outward, and means for securing unitary movement of the handles, and means 5 for locking the handles in vertically adjusted positions.

12. A dust cap for inflating valve stems comprising a body formed to inclose the stem, the body being provided with oppositely disposed slots, a base section telescopically engaging the body for longitudinal movement, a closure disposed within the body and adapted to bear against the upper end of the valve stem, a coil spring bearing 10 at one end against the base section and at its opposite end operatively connected to the closure, an inner sleeve adapted to closely surround the valve stem and formed with longitudinally extending slots, one portion 15 of the sleeve having interior screw-threads adapted to engage the screw-threads of the valve stem and the opposite portion of the sleeve being slotted, a locking segment disposed in said slot and having interior screw-threads, a spring supporting one end of the locking segment and urging the locking segment inward toward the axis of the sleeve, and means for increasing or decreasing the 20 tension on the first named spring and engaging or releasing said locking segment comprising handles having shanks extending through said slots in the body and into the slots in the sleeve, one of said handles carrying a wedge adapted, when 25 the handle is shifted, to engage the locking segment and shift it outward, and means for securing unitary movement of the handles, and means for locking the handles in vertically adjusted positions, said means 30 including catches mounted on the handles, and notches in the body adjacent the slots of the handles into which said catches are 35 adapted to engage.

13. A dust cap for inflating valve stems comprising a body formed to inclose the stem and longitudinally slotted at opposite points, a valve stem closure mounted within the outer portion of the body and adapted to engage against the end of the valve 40 stem, a base section telescopically engaged with the inner end of the body, a coil spring engaging at one end against said base section and at its opposite end connected to the closure, an inner sleeve mounted on the 45 body and adapted to closely surround the valve stem, this inner sleeve at one point in its length being formed with interior screw-threads and with an oppositely disposed slot, an interiorly screw-threaded segmental locking member mounted in said slot, a 50 spring supporting one end of the member and urging the member inward toward the axis of the sleeve, said inner sleeve being longitudinally slotted opposite to the slots in the body, a ring disposed exteriorly of 55 the interior sleeve and interiorly of the body, handle members having shanks passing through the slots in the body and engaging said ring, one of said shanks extending inward beyond the ring and being provided with a wedge adapted to engage the 60 free end of the segmental locking member, and means for locking the handles in vertically adjusted positions including catches mounted on the handles, the walls of the 65 slots through which the handles pass being formed with notches with which said handles engage, slides adapted to close the slots in the body and through which the shanks of the handles pass, the slides being thereby movable with the handles, said shanks extending outward beyond the said closure, and a compression spring carried by said slides and bearing against the closure to urge it against the valve stem, said 70 spring being compressed by a movement of the handles in a direction away from the closure and relaxed by a movement of the handles in a direction toward the closure.

in the body, a ring disposed exteriorly of 65 the interior sleeve and interiorly of the body, handle members having shanks passing through the slots in the body and engaging said ring, one of said shanks extending inward beyond the ring and being provided with a wedge adapted to engage the free end of the segmental locking member, and means for locking the handles in vertically adjusted positions including catches mounted on the handles, the walls of the 70 slots through which the handles pass being formed with notches with which said handles engage.

14. A dust cap for inflating valve stems comprising a body formed to inclose the stem and longitudinally slotted at opposite points, a valve stem closure mounted within the outer portion of the body and adapted to engage against the end of the valve stem, a base section telescopically engaged with the inner end of the body, a coil spring engaging at one end against said base section and at its opposite end connected to the closure, an inner sleeve mounted on the body and adapted to closely surround the valve stem, this inner sleeve at one point in its length being formed with interior screw-threads and with an oppositely disposed slot, an interiorly screw-threaded segmental locking member mounted in said slot, a 85 spring supporting one end of the member and urging the member inward toward the axis of the sleeve, said inner sleeve being longitudinally slotted opposite to the slots in the body, a ring disposed exteriorly of 90 the interior sleeve and interiorly of the body, handle members having shanks passing through the slots in the body and engaging said ring, one of said shanks extending inward beyond the ring and being provided with a wedge adapted to engage the 95 free end of the segmental locking member, and means for locking the handles in vertically adjusted positions including catches mounted on the handles, the walls of the 100 slots through which the handles pass being formed with notches with which said handles engage, slides adapted to close the slots in the body and through which the shanks of the handles pass, the slides being thereby movable with the handles, said shanks extending outward beyond the said closure, and a compression spring carried by said slides and bearing against the closure to urge it against the valve stem, said 105 spring being compressed by a movement of the handles in a direction away from the closure and relaxed by a movement of the handles in a direction toward the closure.

In testimony whereof I hereunto affix my 110 signature.

EDDIE M. OVERBEY.
